UNITED STATES PATENT OFFICE.

DONALD R. MACBAIN, OF CLEVELAND, OHIO.

MANUFACTURE OF STEAM-BOILERS.

1,002,414.

Specification of Letters Patent. Patented Sept. 5, 1911.

Application filed May 31, 1911. Serial No. 630,439.

To all whom it may concern:

Be it known that I, DONALD R. MACBAIN, of Cleveland, in the county of Cuyahoga and State of Ohio, have invented a certain new 5 and useful Improvement in the Manufacture of Steam-Boilers, of which improvement the following is a specification.

My invention relates to steam boilers of the class in which a plurality of tubes is 10 closed within a shell or body, more particularly those of the "locomotive" type, and its object is to provide means whereby the detrimental action of the unequal expansion of the tubes and shell of the boiler will be 15 effectually counteracted, and the objections resultant upon such unequal expansion be eliminated in the operation of the boiler.

In an application for Letters Patent, filed by me January 3, 1911, Ser. No. 600,545, 20 I have set forth an improved method of manufacture of steam boilers, which, generally stated, consists in mechanically imposing a compressive strain upon the boiler tubes which acts in opposition to the tens 25 sional strain imposed upon them in service by the expansion of the boiler shell, and also a tubular steam boiler in which the tubes are subjected to such compressive strain by being secured in tube sheets which are sprung out- 30 wardly, but without permanent set, in the direction of the length of the tubes.

My present invention, which accords in its basic operative principle and result, with that of my application Ser. No. 600,545, 35 aforesaid, consists in a novel method of imparting initial compressive strain to the tubes of a steam boiler, by sprunging said tubes into a slight longitudinal curvature, and, when so sprung, securing their ends 40 into the tube sheets; also, in a tubular steam boiler in which are combined two tube sheets, and a plurality of tubes, sprung into slight longitudinal curvature and secured at their ends in said tube sheets.

45 The improvement claimed is hereinafter fully set forth.

In the accompanying drawing: Figure 1 is a vertical longitudinal central section through a steam boiler, illustrating an application of my invention; and, Fig. 2, a 50 transverse section, on an enlarged scale, through the same, on the line *a a* of Fig. 1.

55 My invention is herein set forth as applied in the manufacture of a steam boiler of the type which is well known in the art, and is now substantially standard in locomotive

engines, and which comprises, as essential elements, a shell or waist, 1, a firebox, 2, at the rear end thereof, a smoke box, 3, at the front end thereof, and a plurality of fire 60 tubes, 4, extending between and secured at their opposite ends to, a firebox tube sheet, 2^a, at the front of the firebox, and a front tube sheet, 3^a, adjoining the rear of the smoke box.

65 The successful operation, in practical railroad service, of locomotive boilers of the construction above described, particularly when fitted with superheater tubes of comparatively large diameter, which are in use 70 to a considerable extent, has been and is materially impaired by leakage at the joints between the tubes and the firebox tube sheets, such leakage involving waste of fuel, 75 delays of trains, and loss of time and expense in frequent repairs. It has been conclusively demonstrated that, with a high firebox temperature and rapid circulation of water, the expansion of the shell of the boiler, between the tube sheets, is greater 80 than that of the tubes, from which unequal expansion there results the exertion of tensile strain on the tubes and their connections to the tube sheets. If the tubes were, or could be, so connected to the front tube 85 sheet as to be capable of slipping therein, that is of moving longitudinally relatively thereto, without leakage at their joints with the sheet, the difference of expansion would be compensated without objectionable results, 90 but as the tubes are rigidly connected to the front tube sheet, the tensile strain is exerted upon the tube beads at the firebox tube sheet, straining them to such an extent that upon a slight reduction of the temperature 95 of the boiler, leaks will be caused between the tubes and tube sheets. As is well recognized by those familiar with the operation of locomotives, this leakage is a serious objection in service.

100 Inasmuch as the condition of unequal expansion of the shell and tubes, which is the cause of the leakage of the latter, by imposing tensile strain upon them, cannot be prevented, my invention is designed to prevent its effect upon the tubes from being injurious, by imposing upon them a counter-acting strain in the opposite direction, *i. e.*, one of compression, and thereby instituting a balance of forces which will eliminate the 105 objectionable result produced in steam boilers of the ordinary construction. To this 110

end, in the practice of my invention, the tubes, 4, are, prior to being set in the tube sheets, 2^a, and 3^a, sprung into a slight longitudinal curvature, as, into an arc, the versed sine of which may be, in a locomotive boiler of the dimensions which are common in locomotives, for fast passenger or heavy freight railroad service, say, 1¹/₂ inches or thereabout, its length varying, in the discretion of the constructor, in accordance with the size of the boiler, and the conditions of service operation. The tubes, 4, may be sprung upwardly, downwardly, or laterally, relatively to the center line of the boiler, as may be preferred or be in accordance with permissible clearance, or some of them may be sprung in one direction and others in other directions. As shown in the drawings, the tubes located above the longitudinal horizontal central plane of the boiler are sprung upwardly, and those below said plane are sprung downwardly, but neither this nor any other specific relative disposition of the curvature of the tubes is an essential of my invention.

The ends of the tubes, when the tubes are sprung out of normal axial line, as above described, are inserted in the holes of the tube sheets, 2^a and 3^a, and secured therein, by expanding in the usual manner, and when so connected to the tube sheets, they are, by reason of their tendency to resume their normal straight longitudinal direction, subjected to an initial strain of compression. When, under the influence of sufficiently high temperature, the expansion of the shell, 1, exceeds that of the tubes, the tensile strain on the latter, induced by such unequal expansion, is counteracted by the initial compression exerted on the tubes by being sprung out of line, which compression is relieved in accordance with the expansion of the shell of the boiler.

It will be apparent to those skilled in the art, that my invention is applicable, without departure from its essential and characteristic principle and features, in the manufacture of tubular steam boilers of types which are structurally different from that which is herein exemplified, and also that the extent and direction of the curvature of the tubes

are matters within the discretion of a competent constructor and may be varied as conditions indicate to be desirable.

I claim as my invention, and desire to secure by Letters Patent:

1. The improvement in the manufacture of steam boilers which consists in the act of mechanically imposing a compressive strain upon the boiler tubes which opposes the tensile strain imposed upon them in service under the greater expansion of the boiler shell, by springing the boiler tubes into a slight longitudinal curvature, and, when so sprung, securing their ends into the tube sheets, thereby producing a state or condition in which said tensile strain is compensated and counteracted.

2. The improvement in the manufacture of steam boilers which consists in the successive acts of springing the boiler tubes into a slight longitudinal curvature, and thereafter mechanically imposing a compressive strain upon them by securing their ends, when they are so sprung, in tube sheets, thereby producing a state or condition in which the tensile strain upon the tubes due to the greater expansion of the shell is compensated and counteracted.

3. A tubular steam boiler, the tubes of which are sprung into slight longitudinal curvature, so as to impose upon them, when set, compressive strain in opposition to the tensile strain imposed upon them by the expansion of the boiler shell.

4. A tubular steam boiler, the tubes of which are sprung into slight longitudinal curvature, and, as so curved, are secured at their ends in tube sheets, so as to be subject to compressive strain in opposition to the tensile strain imposed upon them by the expansion of the boiler shell.

5. The combination, in a tubular steam boiler, of a shell, two tube sheets, and a plurality of boiler tubes which are sprung into slight longitudinal curvature and are connected, at their opposite ends, to said tube sheets.

DONALD R. MACBAIN.
